UNITED STATES PATENT OFFICE

FERDINAND S. OPPENHEIM, OF NEW YORK, N. Y.

CONTAINER

Application filed September 10, 1924. Serial No. 736,807.

This invention relates to packing and shipping boxes and cases. More particularly, it is directed to an improved form of double walled container or carton constructed of 5 corrugated paper board or the like material for packing and shipping delicate apparatus such as radio sets, meters, typewriters and the like.

An object of the invention is to provide 10 a container or carton of the character described having an improved construction and arrangement of inner walls and enclosures for effectively protecting and cushioning radio sets encased in highly finished cabinets or the like from sudden blows and contacts so as to prevent possible injury and damage due to careless and rough handling during transportation.

A further object of the invention is to provide 20 in a container a wall cushioning member which is adapted to serve as an enclosure for supplementary parts of the contents, as for example when the latter is an indoor antenna type of radio set, the "knock down" 25 loop may be fitted into the said cushioning member as will hereinafter more fully appear.

Another object of the invention is to provide 30 an improved container or carton of the character described which is of simple construction, inexpensive to manufacture, and efficient to a high degree for the purposes described.

Other objects of this invention will in part 35 be obvious and in part hereinafter pointed out.

Certain features herein shown and described are shown, described and claimed in 40 my co-pending application Serial No. 736,806 filed Sept. 10, 1924, and accordingly are not claimed herein.

With the above exception, the invention accordingly consists in the features of construction, combinations of elements and arrangement of parts which will be exemplified in the construction hereinafter described and of which the scope of application will be indicated in the following claims.

50 In the accompanying drawing, in which

is shown one of the various possible illustrative embodiments of this invention,

Fig. 1 is a perspective view showing a packing and shipping box embodying the invention, parts of the box being broken away to 55 show the interior construction;

Fig. 2 is a cross-sectional view taken on line 2—2 in Fig. 1 showing the box closed and sealed;

Fig. 3 is a perspective view of one of the 60 end cushioning members or partition liners;

Fig. 4 is a perspective view of a top or bottom cushioning member; and

Fig. 5 is a perspective view of one of the 65 enclosing members.

Referring in detail to the drawing, 10 denotes an outer casing or shell of a packing and shipping box embodying the invention which may have any desired shape or design and may be made of fibre board, card 70 board, or the like material, but is preferably constructed of single or double corrugated paper board, the cellular structure of which has been found to add greatly to the cushioning effect for the purposes described. 75

As seen in Fig. 1, the outer casing is of the usual collapsible construction to permit economical "knock down" shipment and comprises elongated side walls 11, end walls 12, and cover flaps 13, 14, 15, and 16, all preferably formed of a single sheet of material, cut, creased and folded to form the rectangular shaped shell 10, the cover flaps being adapted to fold inwardly to form the top and bottom walls for closing the casing. 85 When the flaps are folded into closed position, they may be held in place by any suitable means, as for example a strip of adhesive tape 17.

Partition liners or cushioning members 80 are provided which are arranged against the side walls 11. These members may be substantially identical in construction, and as is seen most clearly in Fig. 2, each is preferably formed of a single sheet of corrugated paper 95 board, cut, creased and folded to form a rectangular shaped body portion 19, end walls 20 and side walls 21, said end walls 20 having flap extensions 22 which are bent to extend within and adjacent the side walls 21 100

and held in position by suitable fastening means. The flap extensions 22 or other fastenings for the side and end walls to retain them in their relative positions may be omitted if desired, since it is apparent that when the members 18 are assembled within the casing 10, the structure is self-retaining. (See Fig. 2.)

Another set of partition liners or cushioning members 23 are provided to fit against the end walls 12. Each of these members 23, as seen from Figs. 1 and 3, is similar in construction and shape to the members 18, and has a body portion 24, and end walls 25 having flap extensions 25^a and side walls 26 the flaps 25^a extending within and adjacent the walls 26 and held in position by suitable means. In addition each member 23 has the side walls 26 thereof formed with outwardly extending flaps 26^a which are adapted to be inserted between the side walls 21 of members 18 and the walls of the casing 10 to hold the member 23, against movement, as is clearly shown in Fig. 1 and to make the side wall structure self-sustaining.

It will be understood that the shipping box is of suitable dimensions to enable packing the article or articles therein so as to substantially fill the space marked "A" in Fig. 2, and that the partition liners 18 and 23 are of proper design to completely cover the interior sides and end walls of the casing 10.

Where the contents occupying space "A" (see Fig. 2) comprises a radio set encased in a highly finished cabinet, enveloping members 28 may be provided. Each member 28 as seen from Fig. 5 is preferably formed of a single sheet of corrugated paper body construction similar to member 18 described above, and has a body portion 29, end walls 30 having flap extensions 32, and side walls 31, the flaps extensions extending within and adjacent the walls 31. Said members 28 are adapted to fit snugly about the cabinet included in the contents, each of said members 28 covering substantially a half of the latter as shown in Figs. 1 and 3.

To space and cushion the contents from the top and bottom of the casing 10, a novel form of cushioning member 33 is provided. As seen from Figs. 1 and 4, the top and bottom cushioning member 33 is preferably constructed of a single sheet of corrugated paper board, cut, creased and folded to have a rectangular body portion 34, end walls 35 and side walls 36, said end and side walls having their respective edge portions 35^a and 36^a respectively bent inwardly and alternately overlapping the adjacent one as shown in Fig. 4, as shown at 37 and 38. The members 33 thus constructed form a highly effective braced structure and serve to support and space the contents enclosed in the enveloping member 28 from the top and bottom of the casing.

In the practice of the invention, the side partition liners 18 are first placed in position in the casing and the liners 23 are inserted to hold the inner side walls in their respective positions as is clearly shown in Figs. 1 and 2. Having arranged these liners and a cushioning member 33 in position with their body portions spaced inwardly from the various side walls and bottom of the casing 10, the radio set or other article enveloped in member 28 is then lowered into place, the side walls of the latter abutting against the respective side and end walls formed by liners 18 and 23 and being spaced thereby a substantial distance from the walls of the casing 10. With these parts in position, a cushioning member 33 is inserted in the top opening of the casing 10 with the body portion thereof abutting against the enclosed contents, the member 33 being dimensioned to the proper height to fill the space between the top of the set and the top of the casing. The cover flaps are then folded into position and the casing sealed in any suitable manner as by means of a strip of adhesive tape 17.

It is apparent that accessories and parts may be packed and shipped in the same containers outside of the space marked "A" in Fig. 2, as for example, an indoor type of radio set in space "A" and a "knock-down" loop therefor fitted into the top, bottom or both cushioning members.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter therein set forth or shown in the accompanying drawings is to be interpreted as illustrative and not in a limiting sense.

Having thus described my invention, I claim as new and desire to secure by Letters Patent:—

1. A packing and shipping box comprising an outer casing having separate partition liners therein for each of the sides, a pair of said liners being oppositely disposed and each having side walls and flaps extending outwardly from said walls arranged to be inserted between the other liners and the casing, said liners forming a self-retaining structure in the casing adapted to protect and cushion the enclosed contents against damage during transportation.

2. A packing and shipping box comprising an outer casing having separate partition liners therein for each of the sides and cushioning members for the top walls of the casing, a pair of said liners being oppositely disposed and each having side walls and edge flaps extending from said walls and arranged

to be inserted between the other liners and the casing, said liners forming a self-retaining structure in the casing independent cushioning members.

3. A packing and shipping box comprising an outer casing and a plurality of removable spacing partitions arranged to abut one another and to form the inner walls of the box, at least one of said partitions being formed with end and side walls, said partition walls having the free edge portions thereof folded over to extend inwardly, said portions having one end of each positioned to entirely overlap an end of an adjacent portion and the other end of each of said portions to wholly underlie an end of an adjacent portion to form a braced structure and adapted to serve as a supplementary container, the end and side walls of said partition serving to support and space the partition from the adjacent wall of the outer casing.

4. In a packing and shipping box a cushioning member made of a single piece of corrugated paper board creased and folded to form a rectangular shaped body having end and side walls, said walls having each edge portion thereof bent to extend inwardly, one end of each of said portions being positioned to overlap an end of an adjacent portion and the other end of each of said portions to wholly underlie an end of an adjacent portion to form a braced structure and adapted to serve as a supplementary container, the end and side walls of said member adapted to support and space the member from an interior side of the box.

5. A packing and shipping box comprising an outer casing having separate partition liners arranged therein for each of the sides and top wall of said casing, and an independently formed two-part enclosing receptacle for completely enveloping the contents to be packed, said liners forming a relatively rigid structure for supporting the receptacle from the sides of the casing.

45 6. A packing and shipping box comprising an outer casing, a member for enveloping the contents to be packed, a plurality of removable spacing partition liners arranged to abut one another and the sides of the member to form the inner walls for the box, said liners serving to support said member and contents spaced from the walls of the outer casing, at least one of said liners having a body portion and edge flaps extending from said portion, said flaps being inserted between the other liners and the casing for forming a self-retaining structure in the casing.

In testimony whereof I affix my signature.

FERDINAND S. OPPENHEIM.
